UNITED STATES PATENT OFFICE.

PAUL WAGRET, OF ESCAUTPONT, NEAR FRESNES, FRANCE.

MANUFACTURE OF BOTTLES, FLASKS, AND THE LIKE.

No. 818,134.

Specification of Letters Patent.

Patented April 17, 1906.

Application filed July 21, 1904. Serial No. 217,597.

To all whom it may concern:

Be it known that I, PAUL WAGRET, a citizen of the Republic of France, and a resident of Escautpont near Fresnes, Nord, France, have invented certain new and useful Improvements in the Manufacture of Bottles, Flasks, and the Like, of which the following is a specification.

This invention relates to an apparatus for distributing sawdust to the molds in the manufacture of bottles, flasks, or the like, said sawdust to take the place of the wood chips or shavings heretofore used which have been introduced into the molds and which when the molten material is introduced causes said chips to carbonize, and thus act as a lubricant for the walls of the mold and prevent the glass from adhering to them.

An apparatus according to this invention is illustrated, by way of example, in the accompanying drawings, in which—

Figure 1 shows the apparatus in section viewed from the side with reference to the place it occupies in front of the blower. Fig. 2 is a section of the apparatus in front elevation. Fig. 3 is an outside view of the apparatus viewed from the side. Fig. 4 is a front elevation of the apparatus. Fig. 5 is a plan view of the apparatus.

The apparatus consists of a funnel-shaped cast-iron casing or hopper A, adapted to contain the sawdust. The lower narrow portion of the casing is open and allows the sawdust to escape, the quantity of sawdust discharged being regulated by means of a slide B or the like sliding in horizontal grooves in the walls of the casing A.

The slide B, operated by means of a lever C, is extended outside by means of a cylindrical rod supported at D and surrounded by a helical spring E. The slide B is provided at F with a hole through which passes the lower end of the operating-lever C, pivoted about a pin N, secured to the side of the casing A. This slide B is provided within the casing A with another hole through which passes a movable rod G, with a flange to prevent it falling through the hole, said rod being maintained in vertical position and break-

ing up and setting in motion the sawdust at 50 each stroke of the lever.

A set-screw H can be provided to limit the motion of the slide-rod. By advancing or withdrawing this screw as the slide B is moved by the lower extremity of the lever C, 55 which controls it, the quantity of the sawdust discharged can be regulated as desired.

The apparatus is filled from the top with sawdust through an opening K, closed by a horizontally-pivoted plate. It is secured to 60 some suitable part of the bottle-blower by means of angle-pieces I, secured to its upper part.

To the tube terminating the lower portion of the casing A is connected an extension-pipe 65 L for guiding the sawdust to the bottle-mold. The pipe L can be raised or lowered in accordance with the height of the mold and is supported by a bracket J, adjustable on a vertical standard of the catch of the blower. 70

A bracket M, Figs. 3 and 4, the upper portion of which is provided with a horizontal groove, is secured to the bottom of the casing A and supports at D the cylindrical rod, which forms the extension of the slide B. 75 The said bracket is provided with a tapped hole in which moves the set-screw H.

When using the apparatus, the operator presses the lever C, the lower end of which, engaging with the hole F in the slide B, 80 causes the latter to move, compressing at the same time the spring E.

As long as the operator presses on the lever C the sawdust will fall into the pipe L, which discharges it into the bottle-mold. When 85 the workman ceases to press on the lever C, the spring E expands and moves the slide B back, so that it closes the lower opening of the casing A and cuts off the supply of sawdust.

What I claim as my invention, and desire to secure by Letters Patent, is—

In an apparatus of the character described, the combination with a hopper for containing sawdust having a discharge-opening at its 95 lower end and a tube communicating with said opening and adapted to discharge sawdust into a mold, of a regulating-slide ar-

ranged to control the discharge of sawdust through the discharge-opening of the hopper, a pivoted spring-controlled lever engaging said slide to move the same, and a rod carried by the slide adapted to break up or agitate the sawdust at each stroke of the lever.

5 In testimony whereof I have signed my

name to this specification in the presence of two subscribing witnesses.

PAUL WAGRET.
